UNITED STATES PATENT OFFICE.

ROBERT OTMERE DOHM AND AUGUST J. DOHM, OF DANE, WISCONSIN.

TANK-HEATER.

1,359,159.

Specification of Letters Patent. Patented Nov. 16, 1920.

Application filed March 31, 1920. Serial No. 370,320.

To all whom it may concern:

Be it known that we, ROBERT OTMERE DOHM and AUGUST J. DOHM, citizens of the United States, residing at Dane, in the county 5 of Dane and State of Wisconsin, have invented certain new and useful Improvements in Tank-Heaters, of which the following is a specification.

Our invention relates to water heaters for 10 farm purposes; usually employed for tempering the drinking water in stock watering tanks; and the objects of our invention are, first, to provide a device that presents a maximum heating surface to the water; second, to be able to heat a small amount of 15 water to boiling point if desired; and, third, to control the combustion of fuel, by a new and efficient arrangement of dampers.

We attain these objects by the mechanism 20 shown in the accompanying drawings in which—

Figure 1, is a plan;

Fig. 2, is a vertical longitudinal section, on line A—B Fig. 1,

Fig. 3, is a front elevation;

Fig. 4, is a vertical transverse section, on line C—D, Fig. 2.

Similar numerals refer to similar parts throughout the several views.

The outer casing, comprising side walls 1 and 2, rounded at the lower rear corners, and a continuous plate, which forms the front end 3, the bottom 4, and the rear end 5, said plate is welded to the sides and 30 forms a water tight structure; a second water tight receptacle, is formed of sides 6, and 7, which are rounded at both lower corners, and a plate 8, which forms both ends and the bottom, and is welded to the sides; said sides are flanged outward at the 40 top a distance adapted to rest upon the top flanges 9, of the outer casing when the receptacle is placed within the same, said receptacle is much less in length, and slightly 45 less in width and depth than the outer casing and is disposed in the top thereof, a distance from the front end sufficient to form a fire box 10; a channel 11, is secured to the sides of the fire box in alinement with each other, 50 extending from the rear top to the front side adjacent the bottom, a damper plate 12, provided with a handle 13, is slidably disposed in the channels and extends across the fire box, a grate 14, is provided, which 55 abuts the front end of the receptacle and

covers the bottom of the fire-box to within a distance of the front end, and registers with the lower end of the damper plate 12, thereby forming a narrow air passage 15, in front of the grate. By raising the damper 60 plate 12, or removing the same, the grate can be turned edgewise and taken out of the firebox, facilitating the cleaning of the heater. The receptacle being narrower than the casing, a smoke flue 16, is formed at each 65 side thereof, and a combustion chamber 17, is formed between the bottom 4, of the outer casing and the bottom 8, of the receptacle, said chamber extending from the firebox 10, backward and upward to the smoke 70 outlet 18, said outlet is a cast metal hood, extending across the casing and terminating in a pipe collar 19. A horizontal slideable cover 20, is disposed on flanges 9, on the sides 1, and 2, of the casing and is 75 adapted to be used as a sliding damper, or to entirely cover the firebox. To utilize the entire heating surface of the heater, two or more tubes 21, are provided, extending from the inside of the receptacle to the outside of 80 the casing, permitting water to pass from a watering tank 22, into the receptacle, wooden wedges 23, are provided for closing said tubes by inserting them in loops 85 24, which are secured to the inside of the receptacle in front of the tubes. Holes 25, are located in the flanges 9, of the casing sides 1, and 2, through which rods 26, are disposed for anchoring the heater to the bottom of the tank by means of screw eyes 90 27. A cover 28, with a handle 29, covers the entire receptacle and is prevented from moving endwise by depending flanges 30. When desired to heat a small amount of water to boiling point, put on the cover 28, and 95 insert the wedges 23, in the loops 24, closing the tubes 21.

To use our heater a fire is started in the grate 14, and the damper 12, placed in its lower position, see Figs. 1 and 2, in that 100 position the draft will be in front and under the grate, then regulate the supply of air, by the slideable cover 20, to check the fire, raise the damper 12, and close the cover 20.

Having thus described our invention we 105 claim.

In a device of the kind described, the combination of an outer water tight casing, with an inner water tight compartment, the two connected by tubes, and means for clos- 110

ing the tubes, a firebox between the front ends of the casing and the compartment, a grate near the bottom of the firebox, and a sliding cover and a diagonal damper plate adapted to be used to regulate the locality and supply of air to the grate.

In testimony whereof we affix our signa-

tures in the presence of two subscribing witnesses.

ROBERT OTMERE DOHM
AUGUST J. DOHM.
